DESCRIPTION

See application file for complete search history.

(56) References Cited

FIG. 1 is a front, left and top perspective view of a fruit and vegetable washing machine, showing our new design;
FIG. 2 is a rear, right and bottom perspective view thereof;
FIG. 3 is a perspective view without the base of FIG. 1 thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the fruit and vegetable washing machine that form no part of the claimed design.
